Primary Examiner—Stella M Reid*Assistant Examiner*—Keli L Hill*(74) Attorney, Agent, or Firm*—Perkins Coie LLP(57) **CLAIM**

I claim the ornamental design for an amplifier, as shown and described.

DESCRIPTION

FIG. 1 is a front isometric view of an embodiment of an amplifier showing my new design.

FIG. 2 is a front elevation view of the embodiment.

FIG. 3 is a back elevation view of the embodiment.

FIG. 4 is a top plan view of the embodiment.

FIG. 5 is a bottom plan view of the embodiment.

FIG. 6 is a left side elevation view of the embodiment; and, FIG. 7 is a right side elevation view of the embodiment.

The broken lines shown in the drawings are for illustrative purposes only and form no part of the claimed design.
